RAKE

Lonnie A. Seldomridge, Long Beach, Calif.

Application June 16, 1939, Serial No. 279,436

2 Claims. (Cl. 30—304)

This invention relates to a rake and particularly to the type of rake used in cutting runners of plants such as bermuda grass, and other grasses, which throw out radial runners from the parent plant.

An object of my invention is to provide a novel rake; the tines of which are formed of razor blades, the blades being removably held in the head of the rake.

A further object is to provide a novel rake of the character stated, in which razor blades of the type having a heavy backing strip are effectively removably held in the head of the rake, the rake head being so constructed that one or more of the razor blades may be removed and replaced and when in place these blades are tightly held in position by the simple expedient of bolts, which extend through the head.

A further object is to provide a rake of the character stated, which is simple in construction, inexpensive to manufacture, and effective in operation.

Other objects, advantages and features of invention may appear from the accompanying drawing, the subjoined detailed description, and the appended claims.

In the drawing:

Figure 1 is a fragmentary, plan view of the rake.

Figure 2 is a fragmentary, side elevation of the same.

Figure 3 is a plan view of the rake head with the blades and the handle removed.

Referring more particularly to the drawing, the numeral 1 indicates a rake head, and 2 the handle which is detachably secured to the head. The head 1 consists of a backing strip 3, which extends through the length of the head. A front strip 4 extends across the front of the head. Between the strips 3 and 4, I provide a plurality of blocks 5, which are suitably fixedly attached to the front strip 4 by means of suitable fasteners such as nails, or the like, which extend through the front strip and into the blocks. Razor blades 6 are clamped between the blocks 5 and the blocks are grooved as shown at 7 to receive the heavy backing strip 8 of the razor blades. Through each of the end blocks of the rake head, bolts 9 and 10 extend, and these bolts also extend through the

strips 3 and 4. The purpose of these bolts is to securely hold the strips 3 and 4 in position relative to the blocks 5. Due to the heavy backing strip 8 of the razor blades, the rake head will be 5 slightly curved longitudinally, as shown in Figure 3, and this action also serves to more tightly clamp the razor blades between the blocks when the bolts 9 and 10 are securely tightened. The handle 2 is detachably secured to the head 1, and the lower end of the handle is notched as shown at 11 to receive the head 1. Upper and lower fingers 12, 13, respectively, engage the upper and lower edges of the head 1, and these fingers are securely clamped against the head of the rake by 15 the bolt or bolts 14.

Having described my invention, I claim:

1. In a rake head comprising a yieldable front strip, a plurality of juxtaposed blocks, each block being fixedly attached to the front strip, 20 the abutted faces of the blocks being rabbeted, razor blades mounted between each adjacent pair of blocks, the razor blades each having a heavy shoulder at the back edge, said heavy shoulder fitting into the rabbeted portion of the blocks, 25 said razor blades wedging the blocks apart sufficiently to spring said front strip to slight curvature, a substantially rigid backing strip, means extending through the backing strip and through the front strip, at each end of the rake head, 30 whereby the front strip is pulled against the backing strip, thereby clamping the razor blades in assembled position.

2. In a rake head comprising a yieldable front strip, a plurality of juxtaposed blocks, each 35 block being fixedly attached to the front strip, the abutted faces of the blocks being rabbeted, razor blades mounted between each adjacent pair of blocks, the razor blades each having a heavy shoulder at the back edge, said razor blades wedging 40 the blocks apart sufficiently to spring said front strip to slight curvature, a substantially rigid backing strip, a bolt extending through the front strip and the backing strip at each end of the rake head, thereby pressing the front strip 45 towards the backing strip, and clamping the blades in assembled position.

LONNIE A. SELDOMRIDGE.
